UNITED STATES PATENT OFFICE.

EMIL LAWRENZ, OF DETROIT, MICHIGAN.

BEAM COMPASS.

Application filed May 20, 1927. Serial No. 192,840.

This invention relates to instruments usually known as beam compasses or trammels for scribing circles of larger diameter than can be conveniently drawn by means of ordinary compasses, and its object is to provide an instrument of this character which shall be light, which shall be rigid, and which can be accurately adjusted.

This invention consists in the details of construction illustrated in the accompanying drawing and particularly pointed out in the claims.

In the drawing—

Fig. 1 is a side elevation of my improved beam compass;

Fig. 2 is a longitudinal vertical section of the head provided with removable legs;

Figs. 3 and 4 are sections on the lines 3—3 and 4—4 of Fig. 2 respectively.

Similar reference characters refer to like parts throughout the several views.

The beam 1 is preferably formed with rounded upper and lower edges so that the slots in the heads may have rounded upper and lower walls to conserve strength and stiffness. If desired, the weight of the beam may be reduced by grooving the sides which will not affect the strength thereof to any appreciable extent. The body of the tram head 2 is formed with an upwardly projecting stem 3 which is threaded to receive the milled unit 4, and slideable on this stem is a clamping member 5 provided with two pins 6 which engage the beam, these pins extending through holes 7 in the body of this head parallel to the stem 3 and along its longitudinal plane. I prefer these pins to be round so that the holes that receive them will affect the strength of this head as little as possible. These two pins enable me to get a maximum of gripping action on the beam for a minimum of pressure by the nut.

The tram head 2 is longitudinally grooved in its lower edge to produce the flanges 9, between which the tram point carrier 10 is pivoted on the pin 11 carried by these flanges. The head and the point carrier are recessed to receive the spring 12. A pin 13 extending across the groove 14 in the head 2 extends through the head 15 in the adjusting screw 16 which is threaded to receive the nut 17. The adjacent end of the point carrier 10 is formed with a vertical groove 18 to receive the reduced portion 19 of this nut, a circular flange 20 on the upper end of this reduced portion and a circumferen-

tial shoulder 21 at the lower end thereof being in engagement with the upper and lower faces of the adjacent flanges 23 produced by this groove 18. The point carrier may therefore be swung on the pivot 11 by turning this nut 17 in either direction and any slackness which may occur through wear at the nut 17, will be provided for by the spring 12.

Any desired type of leg may be used in connection with this head but I prefer legs 24 similar to those shown and described in my prior Patent No. 1,284,372, dated Nov. 12, 1918, provided with inclined shanks 25 adapted to enter the socket 26 in the point carrier and be held in position by means of a tapering pin 27 having a thumb nut 28 on its threaded end 29. This leg is longitudinally split at its lower end and bored to receive a pencil 30, a screw 31 being provided to cause the two sides 32 to grip the pencil. Pen or pin legs may be used in the same manner but these legs do not involve any part of the present invention.

The tram head 33 is provided with a stationary leg or tram-point carrier 34 which is grooved in the usual manner to receive the point 35 which passes through a loop 36 on the bolt 37 on which the nut 38 is threaded to secure the point in position. The locking mechanism for this head is similar to that for head 2.

I claim:—

1. In a beam compass, the combination of a beam and a tram head slideable thereon, means to secure the head to the beam, said head being formed with a groove in its lower side, a pivot extending across one end of said groove, a tram-point carrier mounted on said pivot, a tram-point extending down from said carrier, a second pivot pin extending across the opposite end of said groove, a bolt mounted thereon, and a nut on said bolt engaging the adjacent end of the point carrier and adapted to move said carrier to swing said leg.

2. In a beam compass, the combination of a beam and a tram head slideable thereon, means to secure the head to the beam, said head being formed with a groove in its lower side, a pivot extending across one end of said groove, a tram-point carrier mounted on said pivot, a tram-point extending down from said carrier, a second pivot pin extending across the opposite end of said groove, a bolt mounted thereon, and a nut on said bolt en-

gaging the adjacent end of the point carrier and adapted to move said carrier to swing said leg, and a spring between said head and carrier to take up all slackness between the 5 carrier, nut and bolt.

3. In a beam compass, a beam and a tram head provided with a slot to receive said beam, said head having an upwardly extending threaded stem and holes in its central 10 plane parallel to said stem, a clamp slideable on the stem and having pins extending into said holes and into engagement with said beam, a nut on said stem adapted to force said clamp inwardly, and a point carrier 15 projecting from the bottom of said head.

4. In a beam compass, a beam and a tram head provided with a slot to receive said beam, said head having an upwardly projecting stem and openings adjacent thereto, 20 a nut on said stem and a clamping member slideable on the stem and having projections

adapted to extend into said openings into engagement with said beam, and a point carrier projecting from the bottom of said head. 25

5. In a beam compass, the combination of a beam and a tram head slideable thereon, means to secure the head to the beam, said head being formed with a groove in its lower side, a pivot extending across one end of said groove, a tram-point carrier mounted on said pivot, a tram-point extending down from said carrier, a second pivot pin extending across the opposite end of said groove, a bolt mounted thereon, and a nut on said bolt engaging the adjacent end of the point carrier 30 and adapted to move said carrier to swing said leg, said nut having a reduced cylindrical portion with shoulders at the ends thereof, and said point carrier having a notch to receive said reduced portion of the nut, the 35 walls of said notch engaging said shoulders. 40

EMIL LAWRENZ.
